UNITED STATES PATENT OFFICE.

THOMAS E. McDANIEL, OF CHARLESTON, SOUTH CAROLINA, ASSIGNOR TO STANDARD OIL DEVELOPMENT COMPANY, A CORPORATION OF DELAWARE.

BARREL-ROLLING DEVICE.

Application filed July 27, 1925. Serial No. 46,249.

This invention relates to improvements in tools for rolling cylindrical bodies, for example, barrels and drums. The invention will be fully understood from the following 5 description taken in connection with the accompanying drawings, in which:

The figure is a vertical side elevation section of the preferred form of the rolling device constructed according to my invention 10 and showing an end view of a barrel in position for rolling by the use of said device.

In the drawing reference numeral 1 denotes a wheel or roller of large diameter turning on axle 2, the ends of which are held 15 in prongs 3 affixed to handle shaft 4, to the other end of which is affixed handle 5. On said axle 2 and alongside wheel 1 and prong 3 member 6 is pivotally mounted on 2 and extends upwardly to support roller or wheel 20 7 of small diameter turning on axle 8. Notched bar 9 is pivotally mounted on and extends from axle 8 to handle shaft 4 to which is affixed pin 10 on which said notched bar 9 rests in position to be manually drawn 25 back and forth or held in one of several positions by notches in said notched bar in contact with pin 10.

In operation roller or wheel 1 rests on the floor, roller or wheel 7 rests against the outer 30 perimeter of the cylindrical body 11 to be rolled. Notched bar 9 permits adjustment of position of wheel 7 according to size of cylindrical body to be rolled.

This invention may be employed in a tool 35 having one handle 4, one wheel 1 and one wheel 7; or it may be a tool having one handle 4, two or more wheels 1 and two or more wheels 7 as may be most desirable according to the weight and size of the cylindrical body to be rolled. Notched bar 40 9 may be used singly, or two or more such notched bars may be used. When two wheels 1 are employed each will be mounted near one end of elongated axle 2, and when two 45 wheels 7 are used each will be mounted near one end of axle 8, thus requiring two or more members 6 to support axle 8 from axle 2. In case two or more wheels 7 are used notched bar 9 will be affixed to the central portion of 50 axle 8, or notched bar 9 may be made with two prongs each of which will fit over one end of axle 8.

The operation of this invention will be clear from the foregoing description and the 55 accompanying drawing.

As an addition to this invention there may

be used a hook or brake (not shown) extending over the cylindrical body to hold it in position or retard its rolling as may be desired. As another method of braking there 60 may be employed a weight 13, preferably triangular cross-section attached by line 15 to handle 4 at point 14. When weight 13 is not in use it may be carried on handle 4 at about the point shown, and when used it 65 may be thrown forward over barrel to point 13', line 15' then extending around the cylindrical body as shown by dotted line to stop or retard the rolling of the cylindrical body and hold it in position. 70

While, for the purpose of illustration, this invention has been particularly described in connection with cylindrical bodies such as barrels and drums, I contemplate applying it for the purpose of rolling or pushing 75 other types of cylindrical bodies such as logs, cans, poles, etc. It will be understood that my invention is not limited to the precise details or embodiments thereof illustrated and described therein, nor to any feature thereof, 80 and various modifications may be made within the scope of the appended claims in which it is my intention to claim all novelty inherent in the invention as broadly as the prior art permits. 85

I claim:

1. An apparatus for rolling cylindrical bodies comprising a revolvable wheel, an axle therefor, a handle shaft, extensions therefrom, bearings for said axle in the ends of 90 said extensions, pivotal supports from said axle bearing a second axle, a second revolvable wheel on said second axle, a pin in said handle shaft, a notched bar pivotally mounted on said second axle and extending to said 95 pin, the position of said second wheel being adjustable by means of said notched bar extending from said second axle to said pin.

2. An apparatus for rolling cylindrical bodies comprising a revolvable wheel, an 100 axle therefor, a handle shaft, prongs extending therefrom, bearings in the ends of said handle prongs for said axle, supports pivotally mounted on said axle, a second axle pivotally mounted on said supports, a second 105 revolvable wheel mounted on said second axle, means for adjusting the position of said second revolvable wheel with relation to said handle shaft and first aforesaid revolvable wheel.

THOMAS E. McDANIEL.
